FRINGING APPARATUS

Alfred German Rose, Gainsborough, England, assignor to Rose Brothers (Gainsborough) Limited, Gainsborough, England, a British company

Application November 9, 1932, Serial No. 641,938
In Great Britain November 17, 1931

13 Claims. (Cl. 164—45)

This invention relates to apparatus for fringing wrappers for use in connection with wrapping machines. Such apparatus repeatedly slits one or more of the borders of each of a series of wrappers (which may be in the form of a continuous web) so as to produce a fringed effect.

It has been proposed to provide fringing apparatus having helicoidal knives which operate on a moving web to cut a fringe in each of the two longitudinal borders of the web. It has also been proposed to provide fringing apparatus comprising a number of disc-shaped rolls which are arranged in pairs on opposite sides of the web and which are displaced laterally towards the web and simultaneously rotated to slit the web as it passes between the rolls.

According to the present invention an apparatus for fringing a series of wrappers comprises two sets of spaced shearing members which are mounted with the members of each set opposite gaps between the members of the other set, and operating means for moving one or both of the sets to slit the border of a wrapper by a scissor-wise action. Preferably, each member is double-edged and co-operates with the opposite members of the other set on each side of it.

In one constructional form according to the invention the shearing members are formed each as a separate part and are pivotally mounted on a spindle with the cutting edges of one set facing those of the other set.

When the apparatus is arranged to fringe a series of wrappers while they are in motion there is provided, according to a feature of the invention, a support for the shearing members, which support is movable in the direction of travel of the wrappers and means for reciprocating the support so that it moves with a wrapper while the shearing members are slitting that wrapper.

According to another feature of the present invention there is provided a support for a wrapper and a pressure member operable to engage a wrapper and press it against the wrapper support while the shearing members are slitting that wrapper. The pressure member prevents accidental displacement of the wrapper while it is being fringed and is particularly applicable to apparatus which is arranged to fringe a series of separate wrappers. Fringing apparatus constructed in accordance with the present invention will now be described, by way of example only, with reference to the accompanying drawings, in which:

Figure 1 is an elevation of a fringing device constructed in accordance with the invention.

Figure 2 is a section on the line 2—2 of Figure 1.

Figure 3 shows a shearing member employed in the device shown in Figure 1.

Figure 4 shows a modified form of the apparatus shown in Figure 1.

Figure 5 shows in elevation yet a further modified form of the apparatus, and

Figure 6 is a cross-section on the line 6—6 of Figure 5.

Like references indicate like parts in all the figures of the drawings.

Referring first to Figures 1, 2 and 3, a series of wrappers in the form of a continuous web 10 is fed by suitable means (not shown) on to a supporting platform 11 which is carried by a bracket 12. Two fringing devices are arranged, one on each side of the platform 11. As these devices are identical in construction, only one of them will be described. In the arrangement shown in Figures 1 and 2 the web 10 is fed intermittently and the fringing devices operate to slit its two marginal borders while the web is stationary.

Each fringing device comprises a set of shearing members A and a set of two sets of shearing members A'. These members are identical and one of them is shown in Figure 3. Each shearing finger consists of a flat piece of hard steel and is of the same thickness throughout. The members A are provided with two holes 13 and 14 and with a double-edged shearing portion 15. The shearing members are threaded on to a spindle 16 so as to form the two sets of members A and A'. The spindle 16 passes through the holes 13, the members A having their shearing edge 15 facing downwardly and the members A' having their shearing edge facing upwardly. The members of one set are arranged alternately with the members of the other set. The spindle 16 is carried by bearings 17 and 18 in frames 19 and 20 on a base 21.

A rod 34 is passed through the holes 14 in the shearing members A and is secured at its ends in bosses 31 and 38 on arms 32 and 33 by means of nuts 35 and 36. The arms 32 and 33 are integral respectively with sleeves 29 and 30 pivotally mounted on the spindle 16. In this manner the shearing members A are tied together so that they will move as a unit and constitute a fringing element. A rod 51 is passed through the holes of the members A' and is secured at its ends in bosses 54 and 55 on arms 49 and 50 by means

of nuts 52 and 53. The arms 49 and 50 are integral respectively with sleeves 44 and 45 which are mounted on the spindle 16 and secured thereto by pins 46 and 47. The members A and A' are pressed to the left (Figure 1) by a coiled spring 59 which surrounds the spindle 16 and engages the sleeve 45 at one end and a washer 60 at the other. A camshaft 22 is mounted in bearings 23 and 24 and carries two similar cams 25 and 26. The cam 25 is provided with a cam-groove 42 on one side, and a cam-groove 58 on the other side. A roller 39 is carried by an arm 27, which is integral with the sleeve 29, and engages the cam-groove 42, while a roller 56 which is carried by an arm 48 integral with the sleeve 44 engages the cam-groove 58. The sleeve 30 has an integral arm 28 carrying a roller 40 engaging with a groove in the cam 26, which groove is similar to the groove 42. The sleeve 45 also has an integral arm 43 carrying the roller 57 engaging a groove similar to the groove 58 in the cam 26.

The shaft 22 is continuously rotated by suitable mechanism and as it rotates the cams rock the two sets of shearing members towards one another while the web is stationary, so as to form a plurality of parallel slits extending transversely of the web. The cams then separate the two sets of shearing members and maintain them separated while the web is fed forward to bring the next uncut portion of the web into register with the shearing members. The operation is then repeated.

In the modified arrangement shown in Figure 4 the web is fed continuously by a pair of rollers 65 and 66, the web being drawn from a suitable supply roll over a roller 64. The fringing device is identical with that described in Figure 1 except that it is mounted on a movable base 61 which is guided in a guideway 62 in a fixed base 63. The base 61 is connected by a link 71 articulated at 72 to the end of a lever 69 which is pivoted at 70. A roller 73 is carried by a pin 74 on the lever 69 and engages with a cam-groove 75 in a cam 67. The cam 67 is secured to a continuously rotating shaft 68. As the cam revolves it reciprocates the base 61 on which the fringing apparatus is mounted. While the fringing apparatus is moving to the right the shearing members are actuated to slit the web. The fringing apparatus is moved to the left while the shearing members are separated from one another.

The modified arrangement shown in Figures 5 and 6 is arranged to operate on a series of separate webs. The fringing apparatus is similar in construction to that shown in Figure 1 but is mounted on a fixed base 81. The wrappers are fed through the fringing apparatus by a conveyor chain 83 having pushing elements 85. The conveyor chain is carried by a pair of sprocket wheels 84 of which one only is shown. The sprocket wheel 84 is secured on a shaft 86 journalled in bearings 87 in a bracket 88. The shaft 86 is driven intermittently by suitable mechanism, such as a Geneva gear, so that the conveyor chain 83 moves intermittently. The upper lap of the conveyor chain extends through, and is supported in, a groove 89 in a supporting platform 82. A series of individual wrappers 90 (Figure 6) are delivered to the left-hand end of the supporting platform 82 and are fed by the pushing elements 85 into position between the shearing members. The wrapper is guided during this movement by upstanding guiding walls

91. While the conveyor chain is stationary the shearing members are operated to fringe both the borders of the wrapper. The conveyor chain is then moved forward again so as to feed the wrapper out at the right-hand end of the apparatus and feed a new wrapper to the fringing apparatus.

It is desirable that the wrapper should be held against movement while the shearing members are operated. This is done in the following manner:

Two levers 92 and 93 are mounted on the shaft 16. Each of these levers includes a downwardly extending arm and an upwardly extending arm which overlie the supporting platform 82. The upper arms 92 and 93 are connected together by two rods 94, the ends of which are fixed in the arms. These rods carry two pressure members 95 and 96, the pressure members being secured to the rods. The lower arms 92 and 93 engage against pins 97 and 98 carried in the arms 27 and 28 respectively of the fringing apparatus.

It will be recalled that the arms 27 and 28 are rocked clockwise (Figure 6) when the shearing members move together to slit the wrapper. Movement of these arms allows the levers 92 and 93 to rock clockwise also until the pressure members 95 and 96 engage the wrapper and hold it against the supporting platform 82. The arms 92 and 93 may rock clockwise under their own weight or their movement may be assisted by a suitable spring. When the shearing members move apart the pins 97 and 98 will engage the arms 92 and 93 and raise the pressure members 95 and 96 away from the wrapper.

I claim:—

1. Apparatus for fringing a series of wrappers, comprising two sets of double-edged shearing members spaced apart to the extent of their own thickness and mounted with the members of each set opposite the gaps between the members of the other set, and operating means for moving one set of members relatively to and towards the other set to slit the border of a wrapper by a scissor-wise action.

2. Apparatus for fringing a series of wrappers comprising a spindle, two sets of double-edged shearing members pivotally mounted on the spindle with the members of one set alternated with those of the other and with the cutting edges of one set facing those of the other set, and operating means for moving the members of one set relatively to and towards the other set to slit the border of a wrapper by a scissor-wise action.

3. Apparatus for fringing a series of wrappers, comprising a spindle, two sets of double-edged shearing members which are pivotally mounted on the spindle with the members of one set alternating with those of the other and with the cutting edges of one set facing those of the other set, two operating parts each associated with a separate one of the sets of shearing members and pivotally mounted to turn about the axis of the spindle, means for securing the shearing members of each set to the associated operating part to move therewith, and operating means for rocking the operating members about their pivotal axis towards and away from one another.

4. Apparatus for fringing a series of wrappers while they are in motion comprising two sets of spaced shearing members, a support on which the shearing members are mounted with the members of each set opposite the gaps between the members of the other set, operating means for moving one of the sets of members relatively

to and towards the other set to slit the border of a wrapper by a scissor-wise action, a guide whereon the support is mounted for movement in the direction of movement of the wrappers and means for reciprocating said support to move with a wrapper while the shearing members are slitting that wrapper and to move in the reverse direction while the shearing members are separated from one another.

10. Apparatus for fringing a series of wrappers comprising two sets of spaced shearing members which are mounted with the members of each set opposite the gaps between the members of the other set, operating means for moving one of the sets of members relatively to and towards the other set to slit the border of a wrapper by a scissor-wise action, a support for the wrappers and a pressure member movable to engage a wrapper and press it against the wrapper support while the wrapper is being slit.

6. Apparatus for fringing a series of wrappers, comprising two sets of spaced shearing members which are mounted to move towards and away from one another and with the members of each set opposite the gaps between the members of the other set, a support for the wrappers, a pressure member movable to engage a wrapper and press it against the wrapper support, and operating means for moving one of the sets of members relatively to and towards the other set and simultaneously moving the pressure member into engagement with a wrapper.

7. Apparatus for fringing a series of wrappers comprising two sets of double-edged shearing members, a spindle whereon the shearing members are mounted with the members of one set alternated with the members of the other set and with the cutting edges of one set facing those of the other set, an operating part associated with one set of the shearing members and pivotally mounted to turn about the axis of the said spindle, means for securing the members of that set to the operating part, a support for a wrapper, a pressure member movable to engage a wrapper and press it against the wrapper support, a one-way connection between the pressure member and the operating part by which the latter holds the former away from the wrapper support and operating means for moving the operating part towards the other set of elements.

8. Apparatus for fringing a series of wrappers, comprising two sets of spaced shearing members which are mounted with the members of each set opposite the gaps between the members of the other set, a support for the wrappers, a pressure member operable to engage a wrapper and press it against the wrapper support, operating means for actuating the shearing members to move towards one another and the pressure member to engage a wrapper and an intermittently actuated conveyor for conveying the wrappers one by one into register with the shearing members.

9. Apparatus for fringing a series of wrappers, comprising two sets of double-edged shearing members spaced apart to the extent of their own thickness and mounted with the members of

each set opposite the gaps between the members of the other set, operating means for moving one set of members relatively to and towards the other set to slit the border of a wrapper by a scissor-wise action, and means in juxtaposition to said shearing members for supporting a wrapper in a plane to be engaged by said shearing members.

10. Apparatus for fringing a series of wrappers comprising a spindle, two sets of double-edged shearing members pivotally mounted on the spindle with the members of one set alternated with those of the other and with the cutting edges of one set facing those of the other set, operating means for moving the members of one set relatively to and towards the other set to slit the border of a wrapper by a scissor-wise action, and means in juxtaposition to said shearing members for supporting a wrapper in a plane to be engaged by said shearing members.

11. Apparatus for fringing the edges of wrapping sheets, comprising a support for holding a wrapper sheet, the support being of less width than the wrapper, whereby the edges of the sheet overhang the edges of the support, shearing units at each side of the support comprising a plurality of groups of cooperating blade elements, each group being movable relative to the support and to each other and positioned to engage between them the overhanging edges of the sheet at the level of the support, and means for retaining the sheet in position and effecting the longitudinal movement thereof along the support.

12. Apparatus for fringing a series of wrappers, comprising a spindle, an abutment at each end of the spindle, two sets of double-edged shearing members mounted on the spindle with the members of one set alternating with those of the other set, a spring located between one abutment and the shearing members and pressing the latter together and towards the other abutment, operating means for moving one set of members relatively to and towards the other set to slit the border of a wrapper by a scissor-wise action, and means in juxtaposition to said shearing members for supporting a wrapper in a plane to be engaged by said shearing members.

13. Apparatus for fringing a series of wrappers comprising a spindle, an abutment at each end of the spindle, a large number of identical flat shearing members, each formed with a two-edged cutting surface pivoted on the spindle with the cutting surfaces on alternating members facing in the reversed direction to those on the remaining members, a spring located between one abutment and the shearing members and pressing the latter together and towards the other abutment, operating means for moving one set of members relatively to and towards the other set to slit the border of a wrapper by a scissor-wise action, and means in juxtaposition to said shearing members for supporting a wrapper in a plane to be engaged by said shearing members.

ALFRED GERMAN ROSE.
